[57] CLAIM

The ornamental design for a rotary switch handle, especially for electrical devices, as shown and described herein.

DESCRIPTION

FIG. 1 is a top right end perspective view of the rotary switch handle, in accordance with our new design;

FIG. 2 is a top plan view of the rotary switch handle illustrated in FIG. 1;

FIG. 3 is a front side elevational view of the rotary switch handle illustrated in FIGS. 1 and 2;

FIG. 4 is a rear side elevational view of the rotary switch handle illustrated in FIGS. 1-3;

FIG. 5 is a right end elevational view of the rotary switch handle illustrated in FIGS. 1-4;

FIG. 6 is a left end elevational view of the rotary switch handle illustrated in FIGS. 1-5; and,

FIG. 7 is a longitudinal cross-sectional view of the rotary switch handle illustrated in FIGS. 1-6, taken along section line 7—7 of FIG. 6.
